Primary Examiner — Keith J Wilson(74) *Attorney, Agent, or Firm* — Fross Zelnick Lehrman & Zissu, P.C.; Charles T. J. Weigell(57) **CLAIM**

The ornamental design for fluid distribution equipment as shown and described.

DESCRIPTION

FIG. 1 is a front perspective view of fluid distribution equipment showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the fluid distribution equipment that form no part of the claimed design.
